RECTIFIER CIRCUIT

Application filed December 23, 1928. Serial No. 156,602.

The present invention relates to electric circuit connection means for current rectifiers. The invention more particularly relates to circuits for rectifiers of the glass bulb vapor arc type of rectifier in which means are incorporated for preventing connection of full supply current to the rectifier when the output current circuit is open.

Various other objects and advantages of 10 the invention will be obvious from the following particular description of circuits embodying the invention or from an inspection of the accompanying drawings; and the invention also consists in certain new and novel 15 features of construction and combination of parts hereinafter set forth and claimed.

In the accompanying drawings I have shown for purposes of illustration circuits embodying the invention, in which

20 Fig. 1 is a circuit diagram for a full wave rectification circuit and

Fig. 2 is a diagram of a similar circuit in which several rectifiers are connected in series in each wave side of the circuit.

25 In Fig. 1 the transformer primary 1 has an input lead 2 and another input lead 4 in series in which is connected resistor 5. Across said resistor 5 is connected the shunt circuit comprising the lead 6 and the switch 8 therein. The spring 10 tends to hold said

30 8 open from the transformer secondary 12, which is in operative relation to said primary 1, lead 14 connects to the anode 16 of the vapor arc rectifier 18, and from an-

35 other point the lead 20 connects to the anode 22 of the rectifier 24. The filament cathodes 26 and 28 of rectifiers 18 and 24 respectively are heated by suitable sources of current 30 and 32 respectively. Said filaments 26 and

40 28 connect with each other through the lead 34 and from that lead through the lead 36 through the solenoid 38 to an output main 40. A second output main 42 connects with an intermediate point on said transformer

45 secondary 12. In operative relation with said solenoid 38 and the core 48 therein is an armature 46 mounted on said switch 8. Said armature which is attracted when said sole-

50 noid 38 is energized, actuates said switch 8 against said spring 10 to close said switch.

In Fig. 2 in addition to said rectifiers 18 and 24 and in series with each in the respective wave side of the circuit are connected additional vapor arc rectifiers 18', 18' and 24', 24'. The other parts and connections in 55 the circuits are substantially the same as those above described in connection with Figure 1.

It has been found that gas or vapor arc 60 rectifiers such for example as those of the tungar type can when connected to an output load be operated with higher voltages on the input mains in multiple wave rectifying circuits than the rectifiers will stand when there is no load to draw current therefrom. The

65 circuit and apparatus herein described and embodying the present invention permits the use of the rectifiers on circuits of higher voltage than the tubes will stand when the work circuit is opened because when no cur-

70 rent is passing through the work circuit or output circuit and solenoid 38 is not energized said spring 10 will open the switch 8 and throw said resistance 5 in series with the primary 1 and thereby cut down the voltage

75 applied to the transformer and to the rectifier. This resistance 5 upon the closing of the work circuit is immediately shunted by the switch 8 because as soon as the work circuit is closed and current flows therethrough 80 said solenoid 38 is energized, armature 46 is actuated thereby and the resistance 5 is shunted permitting the application of full voltage to the rectifying circuit.

85 While I have shown and described and have pointed out in the annexed claims certain novel features of the invention, it will be understood that various omissions, substitutions and changes in the forms and details of the apparatus illustrated and in its operation may be made by those skilled in the art without departing from the spirit of the invention.

I claim:

90 1. In combination in a system of electric distribution, a transformer having input leads and output leads, a resistance in series in one of said input leads, a shunt circuit across said resistance including a switch, a rectifier and a solenoid in series in said out-

put leads, means tending to hold said switch open, and an armature mounted in operative relation with said solenoid and said switch to be moved by said solenoid to close said switch when said solenoid is energized.

6 2. In combination in a system of electric distribution, a transformer having input leads and output leads, a resistance in series in one of said input leads, a shunt circuit 10 across said resistance including a switch which is normally open, a rectifier and a solenoid in series in said output leads, and an armature mounted in operative relation with said solenoid and said switch to be moved by 15 said solenoid to close said switch when said solenoid is energized.

20 3. In combination in a system of electric distribution, a transformer having input leads and output leads, a resistance in series in one of said input leads, a shunt circuit 25 across said resistance including a switch, a gas or vapor arc rectifier and a solenoid in series in said output leads, means tending to hold said switch open, and an armature mounted in operative relation with said sole- 30 noid and said switch to be moved by said noid to close said switch when said sole- 35 noid is energized.

4. In an electrical distribution system in 30 combination with a gas or vapor arc rectifier, a transformer having a secondary tap connected to an electrode of said rectifier and another tap to a work circuit lead, a connection from an opposite electrode of said 35 rectifier through a solenoid to another work circuit lead, supply leads connected to said transformer having a resistance in series in one of them, a shunt circuit across said re- 40 sistance, a switch in said shunt circuit hav- 45 ing a spring tending to hold it in the open position, an armature in operative relation to said solenoid and to said switch adapted to close said switch when said solenoid is en- ergized.

45 5. In combination in a system of electric distribution, input leads and output leads, a resistance in series in one of said input leads, a shunt circuit across said resistance including a switch, a rectifier and a solenoid 50 in series in said output leads, means tending to hold said switch open, and an armature mounted in operative relation with said sole- 55 noid and said switch to be moved by said sole- noid to close said switch when said sole- noid is energized.

6. In combination in a system of electric distribution, a transformer having input leads and output leads, a resistance in series in one of said input leads, a shunt circuit 60 across said resistance including a switch, said switch being normally open, a rectifier and an electromagnet in series in said output leads, and an armature mounted in operative relation with said electromagnet and said 65 switch to be moved by said electromagnet to

close said switch when said electromagnet is energized.

Signed at Hoboken in the county of Hudson and State of New Jersey this 21st day of December, A. D. 1926.

LEROY J. BUTTOLPH.
